UNITED STATES PATENT OFFICE.

ISABELLA G. DABNEY, OF NEW YORK, N. Y.

DESIGN FOR A LAMP-STAND.

SPECIFICATION forming part of Design No. 15,187, dated August 5, 1884.

Application filed June 2, 1884. Term of patent 7 years.

To all whom it may concern:

Be it known that I, ISABELLA G. DABNEY, a citizen of the United States, residing in the city of New York, in the county and State of New York, have invented and produced a new and original Design for the Shape or Configuration of Lamp-Stands, of which the following is a specification, reference being had to the accompanying photograph, forming a part thereof.

My design has reference to the class of lamp which is usually more or less ornamental, and the photograph accompanying shows my design.

15 The characteristic feature of my design is

the stand or body of the lamp, which presents a general resemblance to a truncated melon, having one end removed, with a beetle or similar insect thereon. The melon stands upon a base composed of leaves, as shown. 20

I claim—

The design for a lamp-stand, the same having a general resemblance to a truncated melon standing upon a base composed of leaves, and having upon its surface a beetle or similar insect, as herein shown and described. 25

ISABELLA G. DABNEY.
